SPACE HEATER

Edwin C. Adams, Pittsburgh, Pa., assignor to Adams Bros. Mfg. Co., Inc., Pittsburgh, Pa., a corporation of Pennsylvania

Application May 8, 1953, Serial No. 24,914

Term of patent 3½ years

(Cl. D81—10)

Fig. 1

Fig. 2

Fig. 1 is a front elevational view of a space heater showing my new design; and

Fig. 2 is a reduced front perspective view thereof.

The top and rear of the heater which project rearwardly from the front portion illustrated in the drawing comprise a plain rectangular housing.

I claim:

The ornamental design for a space heater, substantially as shown and described.
